WASHING MACHINE

Lossie T. Mathews, Hazel Park, Mich.

Application December 13, 1940, Serial No. 369,967

6 Claims. (Cl. 68—58)

This invention relates to washing machines and has particular reference to a machine for industrial use.

An object of the invention is to provide a washing machine which is simple in construction and easy to assemble, and one which provides for a continuous flow of liquid therethrough, whereby greater efficiency is obtained in the washing and rinsing operations with a corresponding saving of water and cleaning agents.

Another object of the invention is the provision of a device of the character referred to in which the water and cleaning agents are pre-mixed and thoroughly mixed before they are introduced into the working compartment of the washer.

A further object of the invention is the provision of a washing machine in which live steam is introduced into the working compartment below the water level in such manner that there is a constant agitation of the water and cleaning agents during the washing operation, in addition to the agitation caused by the rotation of the cylinder.

A further object of the invention is the provision of a washing machine which is so constructed and arranged that it is possible to regulate and maintain a continuous flow, and a predetermined level of water in the machine during the washing operation and to maintain a similar flow and a higher water level in the machine during the rinsing operation, whereby all of the dirt is automatically removed from the cylinder during the washing and rinsing operations.

The foregoing and other objects and advantages of the invention will become more apparent as the description proceeds, reference being made from time to time to the accompanying drawings, in which:

Fig. 1 is a perspective view of a device embodying my invention.

Fig. 2 is a longitudinal vertical section taken through the cylinder of the device illustrated in Fig. 1.

Fig. 3 is a view taken substantially on the line 3—3 of Fig. 2.

Fig. 4 is a view taken substantially on the line 4—4 of Fig. 2.

Fig. 5 is a view taken substantially on the line 5—5 of Fig. 2.

Fig. 6 is a view taken substantially on the line 6—6 of Fig. 2.

Fig. 7 is a view taken substantially on the line 7—7 of Fig. 2.

Fig. 8 is an enlarged fragmentary detail, in

section, of the lower lefthand portion of the cylinder.

Referring now more particularly to the drawings, it will be seen that the device embodying my invention consists generally of a cylinder 10, which is mounted for rotation on suitable supports 11 and driven by means of a suitable source of power, not shown, through the belt 12, pulley 13, shaft 14, sprockets 15 and chains 16, in conventional manner. I prefer to construct the supports 11 sufficiently high so that a wheeled container 17 may readily be placed under the cylinder 10, so that the contents of the cylinder may be readily discharged into the container 17 after the washing and rinsing operations are completed.

Water pipes 18 are brought to the device as illustrated in Fig. 1, so that hot and cold water may be introduced to the interior of the cylinder 10 through the pre-mixing basin 19. I also provide a receptacle 20 for liquid soap or a suitable chemical. The soap or chemical is deposited in the basin 19 where it is pre-mixed with the water from the pipes 18 from whence the mixture is permitted to enter the mixing compartment 30 of the cylinder 10 through the feed member 21 (Fig. 2).

I also provide for the introduction of live steam into the cylinder 10, through the steam line 22 and the bores 23 and 23a, formed in the shaft 24, and the steam lines 25, which are threaded into the bores 23a, as shown in Fig. 2.

The shaft 24 is an integral part of the spider 26, which forms the supporting means for one end of the cylinder 10 and the steam lines 25 and 25a. A plate 27 is secured by bolts 28 to the spider 26 and serves as a closure element for one end of the cylinder 10. The plate 27 is provided with cut-out portions 29, which permit communication between the mixing compartment 30, defined between the end 31 of the cylinder 10 and the plate 27. The end 31 of the cylinder 10 is provided with a central opening 31a through which the member 21 extends into the mixing compartment 30. The inside of the cylinder 10 is provided with a plurality of hollow longitudinal baffles 32 (Figs. 2, 5, and 6). The interior of each baffle 32 is provided with a vertical wall, as at 33, which defines a space 34, which is in communication with the mixing chamber 30, through the openings 29 in the plate 27. The side walls of the baffles 32 are perforated, as at 35, so that the water, soap and chemical mixture may reach the interior of the cylinder 10. The steam lines 25 have extension members 25a which pass through

the spider 26 and the plate 27 and into the spaces 34. The steam line extensions 25a are perforated, as at 36 (Fig. 8), so that the live steam creates a turbulence inside the area 34 and escapes with the soap-chemical water mixture through apertures 35 to the interior of the cylinder 10.

The opposite end of the cylinder 10 is provided with a plate 37 and a spider 38 which is also provided with a shaft 39. The plate 37 is perforated, as at 40 (Figs. 2 and 5) so that water can get from the interior of the cylinder 10 into the area 41, which is defined between the plate 37 and the end of the cylinder 42. The plate 37 is provided with a plurality of fins 37a which agitate the water in the bottom of the area 41 and prevent dirt from settling there. The end 42 is perforated, as at 43, throughout the area between the broken lines 44 and 45. This permits me to maintain at all times a water level of sufficient depth to cover the baffles 32 and to raise the water level by increasing the water flow into the cylinder during the rinsing operation. The spacing, number and size of these perforations determine the out flow. The water which flows out of the cylinder 10 through the apertures 43 is gathered in the collector basin 46, which is permanently fixed at one end of the cylinder 10, as shown in Figs. 1 and 2, and does not rotate. The basin 46 is preferably formed in two sections, as shown in Fig. 7, which sections are secured together by means of welding thereto the angle members 46a. The water collected in the collector basin 46 is exhausted through the drain pipe 47.

With this device I am able to provide a continuous flow of water through the cylinder 10 during the washing and rinsing operations and it is only necessary to watch the color of the exhausted water to determine when the clothes are clean.

The cylinder 10 is loaded through the removable door 48 which is secured in position by means of the fingers 49 and the cam locks 50, which engage suitable openings formed in the channel members 51 which are welded to the outer periphery of the cylinder 10.

From the foregoing, it will be seen that I have provided a washing machine which is simple in construction and one which is suitably adapted to the washing of particularly soiled and dirty fabrics, because I provide for a continuous flow of water through the machine, and for other reasons which are obvious from the description.

Having described my invention, what I claim and desire to secure by Letters Patent is:

1. In a device of the character described, the combination of a rotatable cylinder, a pair of end plates positioned inside the cylinder and secured thereto in spaced relation to the ends thereof, spiders for supporting the end plates, and a trunnion integral with each spider and extending through a respective end wall of the cylinder, the inner periphery of the said cylinder being provided with a plurality of hollow baffles extending from one end plate to the other, each of the said baffles being divided into a small and a large compartment, the small compartment of each baffle being in communication throughout its depth with the space defined by one end wall of the cylinder and one of the end plates.

2. In a device of the character described, the combination of a rotatable cylinder, a pair of end plates positioned inside the cylinder and secured thereto in spaced relation to the ends thereof, spiders for supporting the end plates, and a

trunnion integral with each spider and extending through a respective end wall of the cylinder, the inner periphery of the said cylinder being provided with a plurality of hollow baffles extending from one end plate to the other, each of the said baffles being divided into a small and a large compartment, the small compartment of each baffle being in communication, throughout its depth, with the space defined by one end wall of the cylinder and one of the end plates, and the small compartment of each baffle having apertures in its side walls, communicating with the interior of the cylinder.

3. In a device of the character described, the combination of a rotatable cylinder, a pair of end plates positioned inside the cylinder and secured thereto in spaced relation to the ends thereof, spiders for supporting the end plates, and a trunnion integral with each spider and extending through a respective end wall of the cylinder, the inner periphery of the said cylinder being provided with a plurality of hollow baffles extending from one end plate to the other, each of the said baffles being divided into a small and a large compartment, the small compartment of each baffle being in communication, throughout its depth with the space defined by one end wall of the cylinder and one of the end plates, the small compartment of each baffle having apertures in its side walls communicating with the interior of the cylinder, and a steam pipe extending into the small compartment of each baffle, the said steam pipe having a plurality of apertures adjacent to the top wall of said small compartment.

4. In a device of the character described, the combination of a rotatable cylinder, a pair of end plates positioned inside the cylinder and secured thereto in spaced relation to the ends thereof, spiders for supporting the end plates, and a trunnion integral with each spider and extending through a respective end wall of the cylinder, the inner periphery of the said cylinder being provided with a plurality of hollow baffles extending from one end plate to the other, each of the said baffles being divided into a small and a large compartment, the small compartment of each baffle being in communication, throughout its depth, with the space defined by one end wall of the cylinder and one of the end plates, and the small compartment of each baffle having apertures in its side walls communicating with the interior of the cylinder, and there being apertures in the second end plate substantially throughout its area.

5. In a device of the character described, the combination of a rotatable cylinder, a pair of end plates positioned inside the cylinder and secured thereto in spaced relation to the ends thereof, spiders for supporting the end plates, and a trunnion integral with each spider and extending through a respective end wall of the cylinder, the inner periphery of the said cylinder being provided with a plurality of hollow baffles extending from one end plate to the other, each of the said baffles being divided into a small and a large compartment, the small compartment of each baffle being in communication, throughout its depth, with the space defined by one end wall of the cylinder and one of the end plates, and the small compartment of each baffle having apertures in its side walls communicating with the interior of the cylinder, there being apertures in the second end plate substantially throughout its area, and there being apertures in a predeter-

mined area of the end wall of the cylinder adjacent said second end plate.

6. In a device of the character described, the combination of a rotatable cylinder, a pair of end plates positioned inside the cylinder and secured thereto in spaced relation to the ends thereof, spiders for supporting the end plates, and a trunnion integral with each spider and extending through a respective end wall of the cylinder, the inner periphery of the said cylinder being provided with a plurality of hollow baffles extending from one end plate to the other, each of the said baffles being divided into a small and a large compartment, the small compartment of each

baffle being in communication, throughout its depth, with the space defined by one end wall of the cylinder and one of the end plates, and the small compartment of each baffle having apertures in its side walls communicating with the interior of the cylinder, there being apertures in the second end plate substantially throughout its area, and there being apertures in a predetermined area of the end wall of the cylinder adjacent said second end plate, and there being a plurality of fins on the inside periphery of the cylinder between the second end plate and the adjacent end wall of the cylinder.
